UNITED STATES PATENT OFFICE.

ALVAN B. EWING, OF LEWISBURG, TENNESSEE.

IMPROVEMENT IN INSECT-EXTERMINATORS.

Specification forming part of Letters Patent No. 125,557, dated April 9, 1872.

To all whom it may concern:

Be it known that I, ALVAN B. EWING, of Lewisburg, in the county of Marshall and State of Tennessee, have invented a new and useful Improved Insect-Exterminator, of which the following is a specification:

My invention relates to an improved insect-exterminator, which is capable of being efficiently employed in localities where it is desired to destroy insects; and my invention consists of a vessel in which steam is generated, and in which steam is the exterminating medium, the said vessel being provided with an injecting-tube, a steam-dome, a safety-valve, and one or more fire-chambers, all of which will hereinafter more fully be set forth.

In the drawing, Figure 1 is front view of the improved insect-destroyer; Fig. 2, a plan view; Fig. 3, a cross-section, showing the arrangement of the flues; Fig. 4, a detached section of the safety-valve.

A, in the drawing, represents a vessel of any suitable construction and material, in which the water is contained to be heated and generated into steam. B B are fire-places or flues, which pass vertically through the boiler, and which are provided with grates C C. Immediately below these grates is one or more openings for the purpose of creating a draught to aid in the combustion of the fuel with which to generate to steam. D D are detachable caps inclosing the lower ends of the flues C C, which serve to catch and retain all ashes, &c., which fall through the grates. E is the dome or steam-drum of the boiler, which is provided with a tube, a, in which is a safety-valve, b, so adjusted and regulated, by means of the spiral spring c, as to allow the escape of steam through the pipe e when a surplus force accumulates. It is evident that any other suitable valve than this may be employed, but as it is simple, easily constructed, and effective, I prefer the one mentioned. F is an ejector or discharge-pipe, which projects from the top of the dome E, or directly from the boiler A, and extends down the side of the boiler, and which gradually terminates in a nozzle, J. The ejector F is for the purpose of discharging the steam into the localities infested with insects, and which it is desired to destroy. G is a discharge-cock, which, in the present instance, is arranged at the bottom of the boiler, and is for the purpose of emptying the same of the water when

the apparatus is not in use. H H are handles, which are firmly or detachably secured to the ends of the boilers for the purpose of manipulating the apparatus. I represents a pipe having a funnel, m, arranged in it, which is used to supply the boiler with feed-water. The opening in the funnel is closed by a cork, or otherwise. Instead of this particular means for supplying the boiler, it may be done in any other suitable and convenient manner. By passing the fire-chambers vertically through the boiler there will be a large heating surface, and the water circulating around this surface will become quickly and rapidly heated, and steam generated; much more so than if the fire was placed underneath the boiler, though the latter may be done.

The operation of the apparatus is as follows: The boiler A is supplied with water through the medium of the supply-funnel m, or otherwise, and the fires are started. When the steam begins to generate it will immediately pass through the ejector F and issue from the nozzle d; it is then placed in the locality infested with the insects which it is desired to destroy, and thus effectually exterminate the same. If a surplus force of steam should accumulate in the boiler it will raise the valve b and pass off into the atmosphere.

The above described apparatus may be employed in households for exterminating bed-bugs and other insects, and will be found very efficient and effective in its exterminating qualities. The apparatus is very simple, easily constructed, and will be found of much importance and value in all localities infested with insects.

The improved insect-destroyer may be provided with feet to prevent the flues from touching the floor, and thus burning and injuring the carpet, &c.

Having thus described my invention, what I claim, and desire to secure by Letters Patent, is—

The combination of the boiler A, steam-dome E, injecting-tube F, valve b, and one or more fire-chambers B B, all arranged and operating substantially as and for the purpose set forth.

To the above I have signed my name this 1st day of February, A. D. 1872.

ALVAN B. EWING.
